FLAME SUPPRESSING ARRESTER
CONSTRUCTION

Ralph R. Pittman, North Little Rock, Ark.

Application August 5, 1946, Serial No. 688,571

6 Claims. (Cl. 175—30)

1

This invention relates generally to devices suitable for limiting a rise in voltage, such as might be caused by lightning or a switching surge, of a connected conductor by means of arc-gaps adapted to spark over at a predetermined voltage, together with means for interrupting the passage of current through the gaps following sparkover.

The objects of the present invention include the provision of a self-supporting arrester construction in which the supporting elements are functional elements in the mechanism of arc extinguishment; the provision of means for confining, cooling and venting the gaseous flame attending the operation of a plurality of arresters of the expulsion type; the provision of a simple structure adapted for applications in which a plurality of serially arranged expulsion arrester units is more effective than a single unit; and a construction including means for suppressing noise of operation. Other objects will appear as the description proceeds.

It is now recognized that lightning discharge devices of the expulsion type offer the best means now known for the dissipation of extraneous and superimposed high voltages which appear in electric circuits operating at sufficiently low voltage to permit effective arc extinguishment in a single unit. Application of expulsion arresters for apparatus protection at higher voltages has been commercially uneconomical, for the reason that both the dielectric and mechanical strength requirements necessitate a relatively very thick wall if the device is built as a single arrester unit, and if a plurality of economically designed lower-voltage units are employed in series, the highly conducting gas discharged from the individual units may cause failure by external sparkover, or may bridge and establish damaging arcs between contiguous live parts. Heretofore the structures suggested for deionizing the gaseous flame discharge have generally been of conducting material, and therefore unsuitable for use in transporting the gas from a series circuit arrangement of several units to a single vent, for reasons shortly to appear.

The invention comprises the elements and combinations thereof, features of construction and arrangement of parts exemplified in the drawing and description, and the scope of the invention will be indicated in the accompanying claims.

Fig. 1 of the drawing shows an elevational view of an embodiment of the invention, partly in section, and Fig. 2 is a section taken along the line 2—2 of Fig. 1.

In detail, the supporting members 45 and 46

5 carry a hollow cylindric exhaust chamber 29, of conducting material, to the top of which are rigidly secured in spaced parallel upstanding relationship, by means of the cap screws 22, an expulsion lightning arrester unit and a flame suppressor, designated respectively in their entirety by the reference characters 12 and 13. The intermediate exhaust chamber 27 is mounted on the respective upper ends of the members 12 and 10 13, and has similarly rigidly secured to its top another expulsion arrester and another flame suppressor, and the upper exhaust chamber 24 is similarly mounted on the top of the last-named arrester unit and flame suppressor.

15 Centrally positioned on the top of the upper exhaust chamber 24, is rigidly secured thereto by means of the cap screws 22, an additional expulsion arrester unit 15, extending upwardly therefrom to a point near the line electrode 10, to provide the usual leakage gap 11 therebetween.

20 The expulsion arrester units as here illustrated are similar to, and described as to operation more in detail, in U. S. Patent No. 2,164,720 dated July 4, 1939, granted to Ralph R. Pittman.

25 The expulsion arrester unit 15 includes the upstanding tubular insulator 18, and has secured thereto by means of threaded engagement at its respective ends, the top closure and upper conducting electrode 17, and the lower conducting electrode 21. The tubular insulator 18 contains the eccentrically mounted filler 20, also of insulating material, which partially fills the bore of the tubular insulator. The lower electrode 21 is provided with an upward and internal extension 30 19, the arrangement being such that the weakest electrical path through the device is along the line of abutment of the filler 20 with the inner surface of the tubular insulator 18, and between the upper end of the electrode extension 19 and the upper electrode 17. Following sparkover of the weakest electrical path, any arc ensuing is driven around the filler 20 and concurrently elongated to facilitate arc extinguishment. The openings 23 through the lower electrode 21 are positioned in registration with the opening 25 35 through the top of the upper exhaust chamber 24, and the gaseous flame attending operation of the device is vented only into the exhaust chamber. The device is economically constructed when the tubular insulator 18 and filler 20 are formed of an arc-responsive volatile material, such as hard fiber.

40 The expulsion arrester units 12 differ from the unit 15 only in the matter of form of the respective top closures and upper electrodes, the former

being provided with a flanged upper electrode 26 through which the cap screws 22 upwardly extend to rigidly secure the top of the units to the respective lower surfaces of the exhaust chambers 24 and 27. In a manner similar to that described in connection with the expulsion arrester unit 15, the expulsion arrester units 12 are arranged to exhaust the gaseous flame attending operation respectively through the openings 28 into the exhaust chambers 27 and 29.

A flame suppressor 13 is positioned in electrically parallel relationship with each of the expulsion arrester units 12 between the adjacent ends of the exhaust chambers 24, 27 and 29. Each flame suppressor 13 includes a longitudinally extending tubular insulator 33, to the respective ends of which are threadedly fitted the flanged and the vented fitting 32 and 36. The latter fittings tightly engage the respective end surfaces of the exhaust chambers, and the vent openings 35, in the upper fitting 32, and the vent openings 37, in the lower fitting 36, are respectively arranged to register with the openings 31 respectively in the lower end of the exhaust chambers 24 and 27 and the openings 38 respectively in the upper end of the exhaust chambers 27 and 29, thereby providing an enclosed electrically insulated passageway in communication with the interiors of the chambers 24, 27 and 29. Under certain conditions, hereinafter mentioned, it may be desirable to support a longitudinally extending cylindric element of insulating material 34, having a diameter less than the inside diameter of the tubular insulator 33, within the latter. If so, the filler 34 may be provided with upwardly and downwardly extending recesses at its respective ends, for registration with respectively corresponding upwardly and downwardly extending portions of the end fittings 32 and 36.

To provide a flame-suppressing passageway between the lower exhaust chamber 29 and the surrounding medium, an additional flame suppressor 14 is provided. This flame suppressor may be similar in construction to those previously described, including the longitudinally extending hollow tubular insulator 40, containing the longitudinally extending filler 39. The upper end of the tubular insulator 40 is threadedly secured to the upper flanged fitting 41, the latter being tightly fitted against the lower surface of the exhaust chamber 29, and held in position by the screws 22. Vent openings 42 communicate with the interior of the exhaust chamber 29 through a registering opening 30 through the bottom of the latter, and the lower end of the tube 40 is threadedly fitted with the end fitting 43, through which the vent openings 44 extend in communication with the interior of the tube 40.

If the particular application of the construction is for the purpose of limiting the rise of the conductor 10 to a predetermined magnitude above ground potential, the lower exhaust chamber 29 is connected to ground, as indicated symbolically at 47. With such an arrangement, any voltage sufficiently great to spark over the series arrangement of the external gap 11 and the preferential spark gaps of the three serially arranged expulsion arrester units will cause operation of the arrester units. After sparkover, current passes serially from the electrode 10 via the spark gap 11 to the upper arrester unit 15, thence through another arrester unit 12 to the conducting exhaust chamber 27, thence through another arrester unit 12 to the conducting exhaust chamber 29, and thence to the ground 47.

The incandescent conducting gas from each expulsion arrester unit is exhausted into the exhaust chamber immediately below each arrester unit, causing each exhaust chamber to assume a different potential with respect to ground. To prevent arc transfer along the path through the flame suppressor provided for the egress of the conducting gas, it is necessary that the length of the tubular insulator confining and transporting the gas be so related to the diameter that the dielectric strength of the gas path exceeds the dielectric strength of the parallel arrester unit at current zero of an alternating current circuit. The dielectric strength of the gas passing from one exhaust chamber to the other through the intervening flame suppressor is dependent upon its temperature, and that construction providing effective cooling is most desirable. For this reason, I prefer to first expand the gas in the exhaust chamber and then pass the gas through an annular path bounded by an insulating material which volatilizes when in contact with the gaseous flame. One such material is hard fiber. The evolution of water vapor from the fiber, along with gases, effectively cools the gaseous conducting flame, thereby maintaining the desired dielectric strength of the gas column.

A specific example of a flame suppressor which I have found to be effective in preventing arc transfer embodies a tubular fiber insulator having an internal diameter of 1 inch, and a fiber filler $\frac{1}{8}$ " in diameter, with a length between conducting members at the respective ends internally of the tube of $4\frac{1}{2}$ inches. A flame suppressor so built is satisfactory for use in parallel with expulsion arrester units rated at 9 kv. rms.

From inspection of the drawing, it may be seen that the upper flame suppressor 13 conducts the gas evolved in the upper lightning arrester unit 15 from the exhaust chamber 24 to the exhaust chamber 27; that the intermediate flame suppressor 13 conducts both the gas passing through the upper flame suppressor and the gas evolved in the operation of the upper arrester unit 12, and that the gas evolved in all three arrester units is finally passed into the exhaust chamber 29. Electrically the operation of the device, insofar as danger from flashover outside of the arrester units is concerned, would be satisfactory if the gas and flame collected in the chamber 29 was simply vented downwardly from its bottom. However, the noise of operation is greatly reduced, and the flame cooled, if the lower exhaust chamber 29 is vented through a flame suppressor 14. The dimensions stated above in connection with the flame suppressors 13 are satisfactory for the flame suppressor 14, and, since no voltage is impressed thereacross, and it is therefore not critical as to dielectric strength, it may be made to accomplish any degree of noise suppression or cooling desired.

It will be apparent that other forms of expulsion arresters and insulated flame suppressors may be utilized in carrying out the invention, and it is therefore intended that the drawing and description will be regarded as illustrative of the principles of the invention, rather than limited to the specific embodiment presented.

I claim as my invention:

1. In combination, a plurality of expulsion arrester units including a line terminal arrester unit, a ground terminal arrester unit, and an intermediate arrester unit, each of said units being closed at the upper end and vented at the lower end, closed exhaust chambers of conducting material electrically connecting said arrester

units in a series circuit arrangement such that the vented end of said line terminal arrester unit is connected through one exhaust chamber to the closed end of the intermediate arrester unit and the vented end of the intermediate arrester unit is connected through another exhaust chamber to the closed end of the ground terminal arrester unit, each exhaust chamber having an opening therein through which conducting gas is discharged from the vented end of the associated arrester unit into each exhaust chamber, and means including a tubular insulator joining the adjacent ends of said exhaust chambers in communication with the interiors thereof, said insulator being rigidly fastened at its respective ends to the adjacent ends of said exhaust chambers and providing the only path of egress for gas discharged from said line terminal arrester unit and vent means for discharging gas from said another exhaust chamber to the atmosphere.

2. In combination, a plurality of expulsion arrester units including a line terminal arrester unit, an intermediate arrester unit, and a ground terminal arrester unit, each of said units being closed at the upper end thereof and vented at the lower end thereof, a first hollow exhaust chamber of conducting material mechanically joining and electrically connecting the vented end of said line terminal arrester unit to the closed end of said intermediate arrester unit, a second hollow exhaust chamber mechanically joining and electrically connecting the vented end of said intermediate arrester unit to the closed end of said ground terminal arrester unit, said first exhaust chamber having an opening therein in communication with the vented end of said line terminal arrester unit and said second exhaust chamber having an opening in communication with the vented end of said intermediate arrester unit, flame-suppressing means joining the respective exhaust chambers in communication with the respective interiors thereof, said flame-suppressing means including a hollow tube of insulating material arranged to transport the gaseous products attending operation of said arrester units from one chamber to the other, said flame-suppressing means being constructed and arranged to cool the gaseous products passing therethrough so as to preclude arc formation under the conditions of operation between said exhaust chambers, and vent means for discharging gaseous products from said second exhaust chamber to the atmosphere.

3. In a lightning arrester, in combination, spaced first and second hollow conducting exhaust chambers, a first expulsion arrester unit mounted on the upper end of said first exhaust chamber and arranged to discharge conducting gaseous flame therein when operating, a second expulsion arrester unit spanning the space between the lower end of said first chamber and the upper end of the second chamber and arranged to discharge conducting gaseous flame within the latter concurrently with the discharge from said first expulsion arrester unit, flame-suppressing means mounted between said chambers in spaced parallel relationship with the second arrester unit, said flame-suppressing means comprising a hollow tube of insulating material in communication at each end with the respective exhaust chambers and forming a passageway therebetween, the length of said tube being so related to the cross-sectional area of the passageway within the tube that arc formation through said passageway under the conditions of operation is precluded, and vent means connecting said

second hollow exhaust chamber to the atmosphere.

4. In a lightning arrester construction, in combination, a support, a vented lower chamber of conducting material carried thereby, an explosion lightning arrester unit and a flame suppressor mounted in spaced parallel relationship on the top of said lower chamber and extending upwardly therefrom, an intermediate chamber of conducting material mounted on the respective upper ends of said arrester unit and said flame suppressor, an explosion lightning arrester unit and a flame suppressor mounted in spaced parallel relationship on the top of said intermediate chamber and extending upwardly therefrom, an upper chamber of conducting material mounted on the respective upper ends of said last-named arrester unit and flame suppressor, and an explosion lightning arrester unit mounted on the top of said upper chamber and extending upwardly therefrom, each of the lightning arrester units being vented only at the lower end thereof and each of said chambers having an opening closed by the vented end of the associated arrester unit through which gaseous products attending the operation of said arrester units may discharge into the associated chamber, and each of the flame suppressors including a tubular insulator vented at each end and each of said chambers having an opening therethrough closed by and in registration with the respective vented ends of said flame suppressors.

5. The combination with at least two expulsion lightning arrester units each closed at the upper end and each having a vent only at the lower end for discharging conducting gas from the interior of said arrester units, of a hollow exhaust chamber of conducting material having an opening in the top and an opening in the bottom thereof, means rigidly fastening the vented end of one of said arresters to the top of said exhaust chamber in registration with the opening in the top thereof for closing said opening, means rigidly securing the closed end of another arrester unit to the bottom of said exhaust chamber, a hollow tubular insulator open at each end, means rigidly securing one end of said tubular insulator to the bottom of said exhaust chamber in registration with the opening therein for closing the last-named opening, and a longitudinally extending element of insulating material mounted within said tubular insulator and partially filling the bore thereof for cooling gas passing therethrough, said exhaust chamber having an internal volume substantially greater than the unfilled space within said tubular insulator.

6. In an expulsion lightning arrester construction, in combination, a plurality of exhaust chambers of conducting material disposed in vertical spaced relationship, a plurality of lightning arrester units of the expulsion type each closed at the upper end and each having a vent only at the lower end for discharging conducting gas from the interior of said arrester units, said arrester units being rigidly secured in series circuit relationship between said exhaust chambers, an opening in each of said exhaust chambers closed by the lower end of each arrester unit through which conducting gas is downwardly discharged into the exhaust chamber immediately below each arrester unit, a hollow tubular insulator rigidly secured at its respective ends to the adjacent ends of said exhaust chambers mounted in spaced parallel relationship with said

arrester units, openings in said exhaust chambers at said respective ends closed by said respective ends for providing a closed passageway between said exhaust chambers, an additional arrester unit secured in upstanding position to the top of the uppermost exhaust chamber, an opening in the top of the latter closed by said additional arrester unit through which conducting gas from said additional arrester may be discharged downwardly into said uppermost exhaust chamber, and means venting the lowermost exhaust chamber to the atmosphere.
